UNITED STATES PATENT OFFICE.

WALTER M. BRADLEY, OF NEW HAVEN, CONNECTICUT.

BOWLING-ALLEY.

1,338,284.

Specification of Letters Patent. Patented Apr. 27, 1920.

Application filed November 22, 1919. Serial No. 339,867.

To all whom it may concern:

Be it known that I, WALTER M. BRADLEY, a citizen of the United States, residing at New Haven, in the county of New Haven 5 and State of Connecticut, have invented a new and useful Improvement in Bowling-Alleys; and I do hereby declare the following, when taken in connection with the accompanying drawings and the characters 10 of reference marked thereon, to be a full, clear, and exact description of the same, and which said drawings constitute part of this application, and represent, in—

Figure 1. A plan view of a bowling alley 15 constructed in accordance with my invention.

Fig. 2. A side view partly in section of the same.

Fig. 3. A rear view.

Fig. 4. A face view of one of the cages detached.

Fig. 5. A vertical sectional view of one of the cages showing the gate therein in its normal position.

Fig. 6. A similar view showing the cage in its depressed position and as about to discharge a ball located therein.

Fig. 7. A plan view of the means for raising the cages and releasing the balls.

Fig. 8. A vertical sectional view of the same.

Fig. 9. A broken perspective view of the ball runway showing the stop door therein.

Fig. 10. A face view of the coin actuating mechanism.

Fig. 11. A top view of the same.

Fig. 12. A side view of a cage with an over-balancing weight.

This invention relates to improvement 40 in bowling alleys and particularly to that type in which the ball, when bowled, is driven over an incline so as to rise in the air and engage with or hit an elevated target, the object of the invention being to 45 arrange a bowling alley in connection with ten pins in the form of cages into which the balls may be directed by the skill of the player and which will, when the ball enters the cage, descend and discharge the ball. The 50 invention further consists in certain details of construction and arrangement of parts as will be hereinafter described and particularly recited in the claims.

In carrying out my invention, I employ

a platform or alley 15 provided with an 55 upwardly inclined surface 16. At the rear of the alley I arrange a series of cages 17 which I term aerial ten pins. The fronts 18 of these cages are in the form of ten pins each formed with an opening 19 into 60 the box or cage in each of which is a gate 21 to be more fully hereinafter described. These cages are guided for vertical movement by vertical guides 22 and preferably 65 rollers 23 and 24 will be mounted on the back of the cages to contact with the front face of the guide rods 22 and with rollers 25 and 26 engaging with the rear faces of the said vertical guides 22. Each cage is 70 connected to the end of a cord 27 which extends upward over an idler 28 over an idler 29 thence downward over an idler 30 thence 75 upward and over idlers 31 and 32 to a transverse bar 33 to which all of the cords from the several cages extend. This transverse bar 33 is connected with a cord or 80 cable 34 which extends down around idlers 35 and 36 and thence forward over idlers 37 and 38 to an operating handle 39 at the front end of the alley. On the reach 40 of 85 the cord between the idlers 29 and 30, a counter-balancing weight 41 is connected and on the reach 42 between the idlers 31 and 32 a weight 43 is suspended by which the cages are counter-balanced and any 85 slack in the cords is taken up. Each cage is formed in its bottom with a hole 44 through which may enter a pin 45 fixed in the floor of the alley. The gates 21, before referred to, consist of two arms 46 90 and 47 arranged at right angles to each other and in the normal position the arm 46 stands horizontally and just below the opening 19 so that a ball entering that opening will strike the arm 47 which then 95 stands in a vertical position and rock the trap so as to turn the arm 47 into a horizontal position and the arm 46 into a vertical position in front of the ball so that it cannot escape through the opening 19. A 100 ball 48 bowled by the player and rightly directed will enter one of the cages and the weight of the ball will overcome the counter-balancing weight 41 and cause the cage to descend and as it descends it will 105 pass over the pin 45 which will turn the trap to its normal position and permit the ball 48 to escape. The ball escaping from

the trap will fall onto the floor of the alley, the portion 49 of which is slightly inclined so that the ball will roll forward into a channel 50 in the front of the inclined surface 16 from which it will be guided to one side into a runway 51 or the discharged balls may enter one of the transverse grooves 52 from which they will pass into the runway 51. In the runway 51 near the front of the alley is a door 53 connected to the side of the runway by spring hinges so as to normally stand transversely to the alley and arrest the movement of balls therein but which may be turned into a pocket 54 formed for it in one side of the runway and connected to a bracket 55 on the door 53 is a cord 56 which extends rearward into connections with a block 57. This block 57 is made in two sections connected together with a coin-gate block 58 between them, and each section is formed with a longitudinal opening, enlarged at their outer ends and the inner ends registering with a hole 72 in the coin-gate block 58. The block 57 is arranged in a box 59 through which the cord 34 extends and the block is guided for longitudinal movement by guide rods 60 and 61 which are supported at their ends in bearings 62 and 63. In the center of the box is a coin slot 64 adapted to register with a slot 65 in the coin-gate block 58 and pivotally mounted in this coin slot is a coin-gate 66 adapted to be turned by the weight 35 of a coin 67 up into position in line with the opening 72 in the coin-gate block 58 so as to prevent the passing through that block of an action block 68 secured to the cable 34 which action block is free to move 40 through the block 58 unless the opening in the coin-gate block is closed by the action of a coin. When a coin is dropped into the slot so as to close the gate 66, a rearward pull upon the cable 34 will cause the action block 68 to engage with the coin-gate 66 and a continued pull upon the cable will move the block 57 rearward until the coin slot registers with a coin receptacle 69 into which the coin will escape. After a predetermined 45 number of balls have been bowled, they will collect in the runway in front of the door 53, then if a coin be inserted in the slot 64, a rearward pull upon the cord 34 will cause the action block 68 to engage with the coin-gate 66 and the block 57 will be moved rearward and as it moves rearward it will pull the cord 56 and open the door 53 so as to allow the balls in front of it to roll 50 rearward for access by the player. On the other hand, at any time the player can by pulling the cable 34, reset the cages which as before stated are all counter-balanced so as to remain in their elevated position when the cable 34 has been pulled but each 55 one is free to drop under the added weight 60 65 70 75 80 85 90 95 100 105 110 115 120 125 130

of a ball entering the cage. Preferably and as shown, the cages will be arranged somewhat in the manner of ten pins except that the foremost row will consist of four cages, the next row of three, the third row 70 of two, then a single one arranged centrally. In order to prevent the movement of cages from interfering with each other three of the cages 70 71 and 72 will be guided at one side. Instead of counter-balancing the cages and providing means under the control of the player, each cage may be over balanced by a weight 73, as shown in Fig. 12 of the drawings, and a shelf 74 provided for the weights and so 80 that when a ball enters a cage the weight of the ball will over balance the weight connected with that cage and the cage will descend and then when the ball has been discharged as above described the weight 85 will over balance the cage and raise it to its normal position. With cages thus arranged it will not be necessary to connect the cage cords with the cable 34 and in this case the cable will be connected to one 90 end of a spring 75 as indicated by broken lines in Fig. 7, the other end of the spring being secured to a fixed point so that the block 57 may be moved by the player as described; that when the cable is released 95 the block will be moved forward by the contraction of the spring 74.

I claim:

1. A bowling alley comprising a floor with an inclined section, a series of cages suspended at the rear end of the floor, means for raising said cages, said cages formed with openings in their front walls into which a ball may enter and whereby under the weight of the ball, said cages will descend. 100 105

2. A bowling alley comprising a floor with an inclined section, a series of cages suspended at the rear end of the floor, said cages each counter-balanced, said cages formed with openings in their front walls 110 into which a ball may enter and whereby under the weight of the ball, said cages will descend.

3. A bowling alley comprising a floor arranged intermediate of its length with an upwardly inclined surface, a series of cages suspended at the rear of the alley, means for raising said cages, said cages each formed with an opening, a gate in each cage adapted by the inward movement of a ball to close the opening to the cage and means for turning said gates and discharging the ball when the cages descend. 115 120

4. A bowling alley comprising a floor arranged intermediate of its length with an upwardly inclined surface, a series of cages, suspended at the rear of the alley, means for counter-balancing said cages, said cages each formed with an opening, a gate in each cage adapted by the inward movement 125 130

of a ball to close the opening to the cage and means for turning said gates and discharging the ball when the cages descend.

5. A bowling alley comprising a floor arranged intermediate of its length with an upwardly inclined surface, a series of cages suspended at the rear of the alley, each cage formed with an opening and provided with a gate adapted upon the entrance of a ball 5 to close the opening, said cages formed in their bottoms with holes and pins arranged in line with said cages and adapted to enter the same when the cages descend, whereby the gates are turned and the balls discharged.

6. A bowling alley including a series of counter-balanced suspended cages, the cords by which the cages are suspended all extending to a transverse bar and a cable extending 10 from the bar in position to be moved by the operator.

7. A bowling alley comprising a series of suspended cages into which balls may be thrown, a runway into which said balls are discharged, a door in said runway, a cable 15 extending into position for operation by the player and connection between said cable and said door whereby the balls may be released substantially as described.

8. A bowling alley comprising a series of counter-balanced suspended cages into which balls may be thrown, a runway into which said balls are discharged, a door in said runway, means for raising said cages to their 20 normal position including a cable extending 25 into position for operation by the player

and connection between said cable and said door whereby the balls may be released substantially as described.

9. A bowling alley comprising a series 40 of suspended cages into which balls may be thrown, a runway into which said balls are discharged, a door in said runway, a cable extending into position for operation by the player and connection between said cable 45 and said door whereby the balls may be released substantially as described, including a coin-gate receiving block, a coin-gate in said block and an action block secured to the cable, the movement of which may be 50 arrested by the said coin-gate.

10. A bowling alley comprising a series of counter - balanced suspended cages into which balls may be thrown, a runway into which said balls are discharged, a door in 55 said runway, means for raising said cages to their normal position including a cable extending into position for operation by the player and connection between said cable and said door whereby the balls may be 60 released substantially as described, including a coin-gate receiving block, a coin-gate in said block and an action block secured to the cable, the movement of which may be arrested by the said coin-gate. 65

In testimony whereof, I have signed this specification in the presence of two subscribing witnesses.

WALTER M. BRADLEY.

Witnesses:

GEORGE T. BRADLEY,
MILTON H. BRADLEY.
